PROCESS FOR TREATING HYDROCARBON OILS

Le Roy G. Story, Beacon, N. Y., assignor to The Texas Company, New York, N. Y., a corporation of Delaware

Application July 22, 1932, Serial No. 623,990

2 Claims. (Cl. 196—50)

This invention relates to processes for the treatment of hydrocarbon oils and more particularly to processes for the production of gasoline of high anti-knock value.

5 In accordance with my invention natural gasoline or other motor fuel having a relatively low anti-knock rating is reformed or converted to produce gasoline of higher anti-knock value by the application of heat and pressure. The contained heat of the resulting reformed product is utilized in stripping straight-run gasoline from crude oil, the straight-run gasoline thereafter being combined with the natural gasoline or other product of low anti-knock value undergoing reformation. By utilizing a process embodying these steps production of high anti-knock gasoline may be economically carried out.

10 My invention will be more fully explained in the following description taken in conjunction with the accompanying drawing.

20 The single figure of the drawing is a diagrammatic view of an oil treating system embodying my invention.

25 Referring more particularly to the drawing, natural gasoline or other hydrocarbon motor fuel of low anti-knock value is introduced through a charging line 1 having a valve 2, into heating coil 3 of furnace 4. The heated oil from the coil 3 travels through line 5, heat exchanger 6, and 30 reducing valve 7 into fractionator 8.

35 In the fractionator 8 the products are separated into vapors which pass off through line 9 and condenser 10 into receiving drum 11, and liquid products which are withdrawn from the fractionator through line 12 having valve 61 and are injected into flash chamber or separator 13 through line 14 under pressure generated by pump 15. This pump may be eliminated where the pressure in fractionator 8 is great enough to 40 force the condensate into line 14. Line 14 has a reducing valve 16 therein which serves to lower the pressure on the liquid products, which evaporate in the still 13. The flash chamber has baffle plates 17 therein which serve to separate 45 entrained particles from the vapors, which are carried through vapor line 18 into a second fractionator 19 from which the lighter products pass off as vapors through line 20 and condenser 21 into receiving drum 22. Fractionator 19 has a 50 trap-out plate or other means (not shown) for separating a side stream of naphtha suitable for reformation and this product may be conducted from the fractionator through return line 23 and pump 24 to line 1, which leads to the 55 reformation coil 3. The line 23 has a valve 25

for controlling the flow of side stream liquid from fractionator 19, and a connection 26 is furnished for conducting final naphtha distillate from receiving drum 22 into line 23, so that a portion of this product may be reformed if desirable. 5

10 A conduit 28 having a control valve 29 connects the bottom of fractionator 19 with the return line 23, and a pipe 30, controlled by a valve 31, is also furnished whereby reflux condensate can be withdrawn from the system. Instead of the vapors from the flash chamber passing through line 18 to fractionator 19 they may be diverted through condenser 32 into line 23 by opening valve 33 in line 34 and closing valve 15 15 35 in the line leading to the fractionator.

20 Fresh charging stock, such as crude oil having a gasoline content, is supplied to the system by pump 37 which forces the oil through a conduit 36, cooling coil 38 in fractionator 19, cooling coil 39 in fractionator 8, heating coil 40 in the furnace 4, heat exchanger 6 and line 41 which connects with the conduit 14 leading to the flash chamber or still 13. The heat exchangers 38 and 39 and heating coil 40 may be partially or 25 completely by-passed as desired by proper manipulation of valves 42, 43, 44, 45, 60 and 46. A conduit 47 is also provided for by-passing heated products from coil 3 to fractionator 8 and the amount of fluid by-passed may be regulated by 30 valves 48 and 49.

25 The temperature and pressure maintained in heating coil 3 should be that best adapted for reforming, or improving the anti-knock rating of the gasoline passing therethrough. The temperature may be for example 900° F. to 1200° F. and the pressure of any suitable value, for example several hundred pounds per square inch, although pressure of 1000 to 2000 pounds per square inch may be used. In passing through the heat exchanger 6 the hot products from coil 3 are reduced in temperature to a lower value, e. g. 500° F. The reducing valve 7 may lower the pressure on the products to approximately an atmospheric value or this valve may be adjusted 45 to permit approximately the same pressure to obtain in both the fractionator 8 and heating coil 3. The temperature of the combined products in line 14 may be 350° F. and the pressure may be of any value best suited for a stripping operation. 40 This pressure will usually be low, for example 10 pounds per square inch although somewhat higher pressure may be maintained advantageously to prevent vaporization of the crude oil in the heat exchanger 6. Where low pressure 50 55

is used no pressure reducing action is needed at valve 16, and on the other hand if the higher pressure is used reduction may take place at this valve. The bottoms may be drawn off from 5 the separator 13 through line 50 controlled by valve 51 and be conducted while in a heated condition to some other well known form of cracking system, (not shown) or the oil may be cooled and put in storage.

10 The separator 13 may be so arranged and the temperature and pressure of the products be so correlated that substantially only gasoline of suitable boiling range for motor fuel will be removed therefrom through the vapor line 18. The 15 gasoline removed may be passed entirely into the line 23 leading to heating coil 3 by closing valve 35 and opening valve 33. In this case all of the gasoline products will be subjected to the reformation process. It may be found in certain cases 20 that only the higher boiling point ends of the gasoline-like products need be reformed, the lighter products having a sufficiently high anti-knock rating without such treatment. In this case liquid products may be removed from the 25 fractionator 19 either in the form of reflux condensate through conduit 28 or as a side stream through the pipe line 23, or both. The final products contained in receiving drums 11 and 12 may be blended if desired by opening valve 52 in 30 line 53 and either of the final products or a blend of the two, may be returned to the coil 3 through lines 26 and 23 by proper manipulation of valves 52, 54 and 27. Fifty-five (55) and 56 are valved draw-off lines for distillate from the 35 receivers 11 and 22 respectively, while valved lines 57 and 58 serve as gas vents for these chambers. The reflux condensate not recycled from the bottom of fractionator 19 may be withdrawn from the system through the conduit 30. A corresponding valved line 69 provides a means for 40 withdrawing excess condensate from fractionator 8.

45 In operation gasoline to be reformed to improve its anti-knock value is introduced through the line 1 to heating coil 3 under a temperature of any suitable value determined by the characteristics of the gasoline, for example 900° F. to 1200° F. and a pressure of several hundred pounds per square inch. The heated products pass 50 through heat exchanger 6 and are somewhat cooled thereby, their exit temperature being possibly 500° F. The partially cooled products are then passed through the pressure reducing valve 7 and expanded into fractionator 8 with the result 55 that final end point vapors pass off through the line 9 and are converted to liquid in the condenser 10, the liquid being collected in accumulator drum 11. Fractionation in the column 8 is aided by the action of cooling coil 39 which serves also 60 to heat crude oil or other gasoline containing stock introduced through line 36, as explained hereinafter. The reflux condensate from fractionator 8 is conducted through lines 12 and 14 into the flash chamber or separator 13 along with the heated crude oil. The vapors from the flash chamber are transferred either to the condenser 32 or fractionator 19 while the liquid products from the flash chamber are withdrawn through draw-off line 50. If the vapors are conducted to the condenser 32 they are forced by the pump 24 to the heating coil 3 along with the natural gasoline, but if they are instead directed to the fractionator 19 they are separated into lighter vaporous products and liquid products. The light vaporous products pass over-head, are partially 70 75

condensed by the action of coil 38 and those remaining are carried off to the condenser 21 and receiving drum 22. Liquid products of the desired boiling point are withdrawn from the fractionator either through conduit 28 or pipe 23 or both and without further cooling are introduced into the heating coil 3 by action of pump 24. The products returned to the heating coil by the pump just mentioned should be of a character such that an increase of anti-knock value by reformation is desired and the arrangement of piping which has just been described is provided so that a proper selection may be made. It has been pointed out hereinbefore that the point of removal of the liquids to be returned to the heating coil will depend upon the character of the products being treated as well as the temperature and pressure of the oil in line 14 and the operating characteristics of the flash chamber 13. The lighter products of certain natural or 20 straight-run gasolines sometimes also need reformation to increase their anti-knock value and in this case the final distillate collected in accumulator drums 11 and 22 may be returned individually or together with any of the liquid 25 products which have already been mentioned as subject to reformation. According to one desirable mode of operation only gasoline stripped from the crude charged to the system is passed through heating coil 3, for reformation, the supply of natural gasoline introduced into pipe 1 being cut off.

Economical operation of the system is insured by introducing fresh crude oil or other oil containing a certain amount of gasoline from line 35 36 through pump 31, heat exchanger 38 and 39, heating coil 40 and heat exchanger 6 into the line 14 leading to the flash chamber 13. By this arrangement a large amount of the heat necessary to strip the gasoline content from the crude oil is derived by indirect contact, in heat exchanger 6, with the vaporous products from heating coil 3 and likewise by the added heat directly derived from the hot reflux condensate contributed by fractionator 8. Any added amount of heat necessary or desirable for the stripping operation may be derived from the heating coil 40 of the furnace 4, the amount of heat picked up in this manner being regulated by the proper setting of valves 46 and 60. A certain amount of heat is also picked up by the crude oil in passing through vapor cooling coils 38 and 39 of the fractionating columns.

I have described a particular embodiment of my invention for the purpose of illustration but it should be understood that various modifications and adaptations thereof may be made within the scope of the invention, as set forth by the following claims.

I claim:

1. The method of producing gasoline of high anti-knock value which comprises stripping crude hydrocarbon oil in a stripping zone to produce straight-run gasoline, separating said gasoline into a lighter portion and a heavier portion, cracking said heavier portion at high temperature under superatmospheric pressure to increase its anti-knock value, passing the resulting cracked products, prior to reduction of the pressure thereon, in indirect heat exchange relationship with the crude oil to be stripped, subsequently flashing said cracked products in a zone separate from said stripping zone to form vaporous gasoline products and heavier liquid products, combining said liquid products with said 60 65 70 75 80 85 90 95

crude oil after the preheating thereof by said indirect heat exchange step and introducing the resulting mixture into said stripping zone wherein in said stripping action takes place.

5 2. The method of treating hydrocarbon oil which comprises passing relatively low anti-knock naphtha through a heating zone wherein it is raised to a reforming temperature and subjected to conversion into higher anti-knock gasoline constituents, passing the resulting reformed products in indirect heat exchange relation with fresh relatively heavy charging stock comprising lighter constituents in the gasoline boiling range and heavier constituents which has previously 10 been passed through an externally-fired pre-heating zone, subsequently introducing said re-

formed products into a first zone wherein vapors separate from liquid residue, fractionating resulting vapors and condensing the fractionated vapors to form a light distillate, passing the pre-heated fresh charging stock from said indirect heat exchange step into a second zone wherein vapors separate from liquid residue, combining said liquid residue first-mentioned with said fresh charging stock after the passage thereof in indirect heat exchange with said reformed products 15 to aid in the separation of vapors therefrom, fractionating said vapors last-mentioned to form a light distillate and blending said light distillates to form a final desired product.
